WILLIAM ALLPORT, OF NEW BRITAIN, CONNECTICUT.

Design No. 4,214, dated July 12, 1870.

DESIGN FOR A DOOR-BELL.

The Schedule referred to in these Letters Patent and making part of the same.

To all whom it may concern:

Be it known that I, WILLIAM ALLPORT, of New Britain, in the county of Hartford and State of Connecticut, have invented and produced a new and original Design for Door-Bells, of which the following is a specification.

The nature of my design is fully illustrated in the accompanying drawing, to which reference is made.

A, in the drawing, refers to a bell, which is constructed as shown, it being saucer-shaped, or what is sometimes termed gong-shaped, and provided with a boss or projection at its center for securing it to the building, which may be done by drilling a hole through the projection, and inserting a screw therein.

At about the points indicated in the drawing, apertures B B are provided, which may be of the form shown, or of any other substantially like it, the ob-

ject being to ornament the bell or give it an improved appearance, and at the same time to save the amount of metal which would otherwise be required to fill the spaces thus left vacant.

I prefer to make the bell of a composition of metal, such as is generally used in making bells, but iron or steel may be used in some cases.

I claim as my invention—

The design for a bell, as shown and described.

In testimony whereof I have signed my name to this specification in the presence of two subscribing witnesses.

WILLIAM ALLPORT.

Witnesses:

AUSTIN HART,
G. C. ANDREWS.
